UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed February 27, 1928. Serial No. 257,156.

This invention relates to improvements in railway draft riggings.

One object of my invention is to provide an improved friction shock absorbing device which is especially designed for use in combination with tandem side castings such as are now on many thousands of cars, whereby to provide a more efficient shock absorbing arrangement for such cars.

More specifically, an object of my invention is to provide a friction shock absorbing device of the character above indicated, characterized by the fact that the friction elements are interlocked with the friction shell for the purpose of maintaining the proper over-all length of the device.

Other objects of the invention will more clearly appear from the description and claim hereinafter following.

In the drawings forming a part of this specification, Fig. 1 is a horizontal longitudinal sectional view of a portion of a railway car showing my improvements in connection therewith. Fig. 2 is a vertical longitudinal sectional view of the improved friction gear proper and corresponding to the line 2-2 of Fig. 1. Fig. 3 is a front end elevation of the shock absorbing device proper. Fig. 4 is a vertical transverse sectional view corresponding to the line 4-4 of Fig. 2. Fig. 5 is a perspective view of the improved wedge employed in my device. And Fig. 6 is a detail perspective of one of the shell liners.

In said drawings, channel draft sills of usual construction are indicated at 10, each of which has secured to the inner face thereof a tandem stop casting or cheek plate, designated generally by the reference character A. A portion of the butt of a coupler is indicated at 11 and said coupler is operatively connected to the shock absorbing device by a strap yoke 12. The improved friction gear proper is indicated generally by the reference character B and the same is adapted to be interposed between the usual type of front and rear followers 13 and 14.

Each tandem casting A is of a design well known and is provided with a front main

stop shoulder 15; front intermediate stop shoulder 16; rear intermediate stop shoulder 17; rear main stop shoulder 18, and corresponding limiting stop shoulders 115, 116, 117 and 118. The castings are also of that type wherein the draft gear is adapted to be supported by detachable follower guide straps 19, which are secured in place by short bolts 20 engaged through suitable slots in the bottom webs of the casting at the main posts thereof.

The improved friction gear proper B includes an elongated casting having a friction shell proper 21 at its front end and a spring cage section 22 at its rear end, said section being connected by integral longitudinally extending top and bottom walls 23-23, thus leaving the sides of the casting open at the intermediate portions thereof, as best shown in Fig. 1. The spring cage section 22 is formed with an integral rear wall 24 which bears against the rear follower 14. At its forward end, the cage section 22 is formed with integral laterally extended vertical heavy flanges 25-25 which function as the rear intermediate follower of the tandem arrangement, said follower sections 25 normally engaging the limiting stop shoulders 117.

The friction shell section 21 has top and bottom walls 26-26 and side walls 27-27, the latter being flat and extending vertically on their inner sides and rounded on their outer sides, as best shown in Fig. 3. At its rear end the shell 21 is provided on each side thereof with vertically extending follower sections or flanges 60-60 which normally engage the front intermediate stop shoulders 16. The top and bottom walls 26 each has its inner face formed with a plurality of flat surfaces in different planes, as indicated at 28, 29, 30 and 31, the two edge surfaces 28 and 31 being relatively narrow and the other two surfaces 29 and 30 being relatively wide and all of said surfaces being arranged more or less to correspond with a hexagon. Engageable with said surfaces 28 to 31 inclusive, are correspondingly formed surfaces 128, 129, 130 and 131 on the outer side of a hardened liner designated generally by the ref-

erence C, as shown in detail in Fig. 6. The latter, at its inner end and on its outer side, is provided with corner lugs or flanges 32—32 which engage corresponding notches 33—33 in the corners of the friction shell proper and serve to hold the liners C against longitudinal movement after the liners are in place. On their inner sides, each liner C is provided with a pair of flat friction surfaces 34—35 opposite the surfaces 29 and 30 of the shell, said friction surfaces 34 and 35 converging inwardly of the shell, as best shown in Fig. 2, thus giving the effect of a tapered friction shell. At their outer ends, each liner is provided with corner lugs 36—36 extended inwardly toward the center line of the gear, as shown in Figs. 3 and 6 and the function of which will appear hereinafter.

In the friction gear chosen for illustration, two wedge-shoes D and E are employed. Each shoe is formed on its outer side with two flat friction surfaces 37—38 cooperating with the liner-friction surfaces 34 and 35, respectively. The shoes D and E are of generally like construction except that the shoe D is formed with a blunt wedge face 39 and the shoe E with a keener wedge face 40, said wedge faces 39 and 40 coopearting with correspondingly sloped faces 41 and 42, provided on the pressure-transmitting wedge F. At their inner ends, the shoes D and E bear on a flange 43 which constitutes part of a cup-shaped spring cap 44. The flange 43 bears against the front end of an outer heavy spring coil 45, and the front end of the inner lighter coil 46 is seated in the cup section of the cap, as shown in Fig. 2. The rear ends of the spring coil bear against the spring cage wall 24.

The wedge F is of novel construction and is provided with an outer flat bearing face 47 which contacts with the front follower 13, the vertical height of the wedge being preferably extended by forming wing sections 48—48. Each side of the wedge F is formed with a flat main portion 49 and a laterally extended shoulder or lug section 50 having a forwardly facing flat shoulder 51. Said shoulders 51 are adapted to engage behind the lugs 36 of the liners C, as shown in Figs. 1 and 2, so that the outward movement of the wedge F is positively limited by the shoulders provided by the lugs 36 and which are fixed with respect to the friction shell. In this way, the over-all length of the mechanism is maintained without the aid of a retainer bolt or the like.

To assemble the elements of the friction gear, it is first necessary to insert the spring coils and the spring cap 44 and compress the same. Provision for doing this is made by forming a relatively large hole 52 through the center of the wedge F and it will also be noted that the innermost portions of the wedge sections of the shoes D and E are cut back as

indicated at 53—53. The wedge and shoes are assembled together and the liners assembled on the outer sides of the shoes, the shoes being considerably advanced inwardly of the wedge F. This complete assembly with its reduced vertical height, due to the advanced position of the shoes D and E is inserted into the mouth of the shell 21, the springs being held under preliminary compression by a suitable plunger operating through the wedge F, as above mentioned. The parts thus assembled, and with the shoulders 51 of the wedge engaged behind the shoulders of the liners, are moved into the shell until the liner shoulders 32 come opposite the notches 33 of the shell, whereupon the shoulders are entered in said notches and the spring gradually released, thus forcing the shoes D and E outwardly and compelling the liners to seat properly, after which it is obvious that the friction elements are interlocked with the shell. The cut-back portion 53 of the shoes D and E is provided so as to clear the pressure tool when the shoes are being inserted in the wedge, it being evident that the shoes will necessarily approach each other while in their advanced position on the wedge F. It will further be noted that ample clearance is left between the top and bottom portions of the wedge F and the outer extended ends of the shoes, to admit of the collapsed positioning of the shoes in assembling the parts.

In a buff action, it is evident that the casting of the friction gear is held stationary, the pressure being transmitted to the three sets of shoulders 16—16; 117—117; and 18—18. The ultimate pressure, assuming a full stroke, is further distributed to the stop castings by the follower 13 engaging the limiting stop shoulders 115, it being noted that the front end of the shell 21 is made flush with said shoulders 115. In a draft action, the wedge F is held stationary by the front follower 13 and the shell casting is moved forwardly, thus setting up the friction action within the shell in an obvious manner and the ultimate load being transferred to the side castings against the four sets of stop shoulders 15—15; 116—116; 17—17; and 118—118.

Although I have herein shown and described what I now consider the preferred manner of carrying out my invention, the same is merely illustrative and I contemplate all changes and modifications that come within the scope of the claim appended hereto.

I claim:

In a friction shock absorbing mechanism, the combination with a friction shell having opposed side walls; of a pair of liners bearing on said side walls, said liners having means at inner ends having shouldered engagement with the shell to anchor the same to the shell; a pair of friction shoes having frictional contact with the liners, each liner

having inturned integral retaining fingers at the outer end thereof; a main spring resistance within the shell opposing inward movement of the shoes; and a block having wedging engagement with the shoes, said block having retaining lugs thereon directly engaging with the retaining fingers of the liners to limit outward movement of the wedge and hold the parts of the mechanism assembled.

In witness that I claim the foregoing I have hereunto subscribed my name this 24th day of February, 1928.

JOHN F. O'CONNOR.
